INVENTOR:
HENRY BAETZ

BY Harry Beiner
ATTORNEY

UNITED STATES PATENT OFFICE

HENRY BAETZ, OF ST. LOUIS, MISSOURI

AIR HEATER

Application filed March 21, 1930. Serial No. 437,737.

My invention has relation to improvements in air heaters and it consists in the novel features of construction more fully set forth in the specification and pointed out in the claims.

The object of the present invention is to provide a radiator that may be embodied in an air heater, said radiator comprising a heating element adjacent to the surface of which is fixed an extended radiator surface in contacting relation, and having channels, or passage-ways, for conducting air. The air is, of course, divided into streams by virtue of the shape of the extended surface and these streams are confined between the heated channel walls of the extended surface throughout the entire period that they are passing through the casing. Thus, a decided advantage in efficiency is gained over the type of extended surface now commonly in use, (namely, fins or spines projecting from the heating elements, such as radiator coils) and a heater of my design is capable of radiating the same amount of heat as an old type of heater considerably larger in size. A further object is to provide a heater of high efficiency by a comparatively simple method of construction. These advantages as well as others will be better apparent from a detailed description of the same in connection with the accompanying drawings, in which—

Fig. 1 is a combined side elevation and vertical section of the heater; Fig. 2 is a front elevation with part of the front wall broken away; and Fig. 3 is a fragmentarily detail showing how the extended surface between the heating elements may be arranged in contacting relation with said elements.

Referring to the drawings showing my improved radiator embodied in a unit heater, C represents the heater casing comprising a medial cylindrical part 1 and conical end walls 2 and 3, the former having a flanged air inlet opening 4 in which operates a fan 5 mounted on motor shaft 6 of the motor 7 carried in a supporting spider 8 fixed to the flange 4. The conical wall 3 has an air outlet opening 9 also defined by a flange 10 to which may be connected a hot air distribution pipe if desired. A plurality of heating

elements in the form of hollow rings 11, 12, and 13 are concentrically arranged within the medial part 1 of casing C which elements are connected by several (in the present instance four) series of nipples 14, 15 and 16, the outer nipple 14 of which projects beyond the wall 1 and has its end screw-threaded to receive either a cap 17 or steam pipe 18. There will, of course, be a steam pipe 18 connected to each of two of the pipes 14 (as shown) one of which will serve as the steam inlet and the other as the condensation outlet. The two pipes 14 not in use either as inlet or outlet are closed by caps 17. It is apparent from an inspection of the drawings that steam entering any of the pipes 14 will traverse the heating element 11 from which it will pass through pipe 15 to heating element 12, thence through pipe 16 to heating element 13, and the water of condensation discharges in a reverse manner through pipes 16, 15, and pipe 14, that is utilized as the condensation outlet.

At the center of the casing C is a hollow drum 19 having its end adjacent to the fan 5 closed by a conical cap 20, the wall of said drum being suitably spaced from the heating element 13. The heating element 11 is also spaced from the casing wall 1, and into each of these spaces is arranged extended heating surface. This extended heating surface consists of fluted or zig-zag heat conducting elements 21, 22, 23 and 24 each of which is bent from thin, springy sheet metal so that the fluting is of proper size to allow the elements to be forced into the spaces between heating elements and hold themselves in place by the inherent tension in the material.

The loops *a* of the fluted conducting element provide channels *b* and *c* for the passage of air which is heated by contact with the hot walls of said loops and radiator surface. Obviously, the contacting of the extended surface with the radiator surface along the many lines indicated at *d* (Fig. 3) conducts the heat from the radiator surface to every part of the extended surface.

If desired, I may build a single radiator embodying the principles of the invention, in which case a heating element is arranged

in spaced relation with a supporting or confining wall, and into this space between the surface of the heating element and confining wall is forced the metal fluting for forming 5 the channels for a flow of air.

A radiator so constructed is simple, capable of low cost manufacture, and possesses high efficiency.

Having described my invention, I claim:

- 10 1. In a radiator, heat conducting elements adjacent to the radiator surface, said elements comprising zig-zag or fluted sheets of springy material providing channels for confining air streams, a supporting wall for said sheets disposed in fixed spaced relation and parallel with the radiator surface, one end of each element bearing against the radiator surface and the opposite end of each element bearing against the supporting wall.
- 15 2. An air heater comprising a casing, means for moving air through said casing, a heating element within the casing and spaced therefrom, heat conducting elements comprising corrugated members disposed between the casing and heating element, said corrugated members having channels, the bounding walls of which are confined by their inherent expansive property between the surface of the heating element and the 30 casing.
- 20 3. An air heater comprising a circular casing having an air inlet and air outlet, means for moving air through the casing in paths substantially parallel with the longitudinal axis thereof, a plurality of annular heating elements concentrically disposed in spaced relation within the casing, and heat conducting elements arranged between the heating elements and having channel passages for 35 the flow of air.
- 35 4. An air heater comprising a circular casing having an air inlet and an air outlet, means for moving air through the casing in paths substantially parallel with the longitudinal axis thereof, and an annular heating element disposed within said casing in parallelism with and spaced from the wall thereof, a heat conducting element arranged between the heating element and the casing, said conducting element comprising a fluted sheet of springy material to provide air passages 45 through the casing and held in place by its expansive force exerted against the casing and heating element.
- 50 5. In testimony whereof I hereunto affix my signature.

HENRY BAETZ.
